US00D551237S

(12) **United States Design Patent** (10) **Patent No.:** **US D551,237 S**
Hering (45) **Date of Patent:** **** Sep. 18, 2007**

(54) **SET OF KEY BUTTONS FOR A
COMMUNICATOR**

(75) Inventor: **Jean-Marc Hering**, Salo (FI)

(73) Assignee: **Nokia Corporation**, Espoo (FI)

(**) Term: **14 Years**

(21) Appl. No.: **29/270,955**

(22) Filed: **Jan. 8, 2007**

Related U.S. Application Data

(62) Division of application No. 29/224,327, filed on Mar. 1, 2005.

(51) **LOC (8) Cl. 14-02**

(52) **U.S. Cl. D14/455**

(57) **CLAIM**

The ornamental design for a set of key buttons for a communicator, as shown and described.

DESCRIPTION

FIG. 1 is a front view of a set of key buttons for a communicator showing my new design in the environment of a keypad; and,

FIG. 2 is a perspective view thereof.

The broken line showing the various disclaimed regions in the figures is for illustrative purposes only and forms no part of the claimed design.
